SIGNALING DEVICE.

1,364,536.

Specification of Letters Patent.

Patented Jan. 4, 1921.

Application filed October 16, 1916. Serial No. 125,848.

To all whom it may concern:

Be it known that I, BRENNAN B. WEST, a citizen of the United States, residing at Lakewood, in the county of Cuyahoga and State of Ohio, have invented a certain new and useful Improvement in Signaling Devices, of which the following is a full, clear, and exact description, reference being had to the accompanying drawings.

10 This invention relates to signaling devices for vehicles; and it has for its object the production of a comparatively simple signaling device that is especially adapted for use on automobiles, and that is extremely convenient of operation and highly effectual as a day and night signal.

A further object of the invention is the production of a signaling device involving a pair of direction indicators which are adapted to be moved, one at a time, from normal to respective second positions to indicate each a direction opposite to that indicated by the other, or which are adapted to occupy their respective second positions simultaneously thereby to counteract or nullify their independent effects; the device, in its preferred form, further involving an indication which is concealed by the direction indicators when in their normal positions but revealed when both of said indicators are simultaneously in their second positions.

In the accompanying drawings which form a part hereof and wherein similar reference characters designate corresponding parts throughout the several views, Figure 1 is a perspective view of the signaling device and the elements through which it is operated; Fig. 2 is a central vertical section through the device; Fig. 3 is a vertical section on the line 3—3 of Fig. 2; Fig. 4 a horizontal section on line 4—4 of Fig. 3; Figs. 5, 6 and 7 are perspective views of parts of the device; and Fig. 8 is a sectional detail through the pedal attachment and includes a diagram of the electric circuit associated therewith through which the device is operated.

In the present embodiment of my invention, the device comprises a casing 1 which is made up of a circular and a cylindrical wall, the latter being designated 2 and having its free edge turned outward to provide a flange 3 against which a similar flange 4

of a cover 5 is adapted to be held by a channel member 6, preferably formed in halves that are pivoted together as by a rivet 7, the free ends of the halves being connected together by any suitable means, thereby to hold the channel member 6 snugly about the 60 casing and retain the parts securely together. A segmental sight opening 10 is formed in the lower portion of the cover 5, and the upper and central portions thereof are bulged outward (for a purpose which 55 will hereinafter be explained) and at its center, the cover is provided with an opening occupied by a lens 11 of some suitable color adapting it to the purpose of a "tail light." The opening 10 is covered by a 70 glass 12, shown as held in place by clips 13. The cylindrical wall of the casing has an opening 15 formed in its lower portion, and a curved plate 16 of glass or other suitable translucent material is shown as held over 75 the opening by clips 17.

A tubular post or arbor 20 is located central of the casing and its externally threaded end 21 has applied to it a nut 22, such end, beyond the nut, being passed through 80 an aperture in the circular wall of the casing. The protruding end of the post has applied to it, preferably by threading it thereupon, a supporting plate 23. Thus it will be seen that the central portion of the 85 circular wall of the casing is clamped between the plate 23 and the nut 22; and if found necessary, an additional nut 24 may be applied to the outer end of the post to more positively lock the parts against 90 unscrewing or loosening. The plate 23 extends upward to within a short distance of the top of the casing 2 and bolts 25 are passed through spaced aperture 25^a of the plate and through alining apertures in the 95 circular wall of the casing. On the inside of the casing, one flange of an angle bracket 26 is applied to the bolts and is sustained thereby in a position to support, from its other or horizontal flange, a pair of solenoids 27 and 28, the solenoids being attached to the bracket by screws 29. The lower end of the supporting plate 23 has a threaded aperture 30 for the reception of the threaded shank of a stop pin 31 which 105 is located inside the casing and passes through an aperture in its circular wall, the pin being located a short distance below and

in the vertical plane of the axis of the post or arbor 20. The supporting plate 23 is provided with a hollow cylindrical boss 32, shown as having a set screw 33 threaded through one side, for application to a suitable lamp bracket.

In Fig. 6 I have shown in perspective a direction indicator 35 that is preferably stamped from a thin sheet of light weight metal, the same being designed, when finished as I will presently explain, to give the appearance of an arrow head from each side of which extends a segmental wing 37, the two wings preferably including something more than 90° of a circle. I employ two of these direction indicators in my device and the wings 37 thereof are preferably finished or colored to correspond to the interior of the casing 1, while the arrow head portion of each is finished in a distinctive color. For instance, the arrow head of one may be green, while that of the other may be red, and the interior of the casing, with the wings of each indicator, may be white.

The stem of each indicator has an aperture 38 which is in axial alinement with the arrow head, and it may be explained that the center of this aperture constitutes that whereon the segment of the wings 37 is laid out. In Fig. 7 I have shown an arm 40, one of such arms being designed for attachment to each of the direction indicators 35, the arm having a hub portion 41 that is provided with an opening corresponding substantially in size to the aperture 38 of the indicator and that is intended to register therewith, the outer end of the arm being perforated at 42 for the reception of a pin, rivet, or other securing means which also passes through a hole 43 in the indicator. While the direction indicators are identical in outline, I preferably attach their respective arms 40 to different sides so that they may be mounted upon the post 20 with their hubs extending in the same direction from the indicators, while the indicators themselves are reversed with respect to each other. It will be observed that the stem of each indicator is offset laterally and that a notch 44 in the side thereof extends slightly beyond the central axis of the arrow so that when the indicators are suspended upon the post 20 they fall to normal position with their notches 44 occupied by the stop pin 31.

The lower ends of links 45 are pivoted to the direction indicators preferably by the same means that connect the free ends of the arms 40 to the indicators. The upper end of each link 45 is pivotally connected to the core of the previously mentioned solenoid that is located above it, so that when the solenoid is energized and its core is sucked inward, it will swing the direction indicator upward into a horizontal position, the length of movement of the core being

such as will swing the indicator through substantially 90°.

To the rear of the direction indicators, when they are in normal position, is located, in the zone of their wings, an indication represented in the drawings by the word "Stop," and designated 48, the same being shown as printed upon the circular wall of the casing opposite the sight opening 10, although it will be understood that the same might be immovably supported within the casing in any suitable manner. When either or both of the indicators are in normal position they conceal the indication 48; but when both simultaneously occupy their second positions, the indication is revealed to view through the sight opening 10.

An electric light socket 50 is attached to the inner end of the hollow post or arbor 20 preferably by having a threaded extension 51 thereof screwed into the internally threaded end of the post or arbor. A suitable conduit 52 leads into the outer end of the post through which wires 53 pass to the socket 50. I have also shown the wires which lead to the solenoids 27 and 28 as conducted through the conduit 52, the wires being turned laterally through openings formed in the post and nut 22, and being retained against displacement by a suitable clip 54, attached to the circular wall of the casing. An electric lamp 55 is supported by the socket 50 centrally within the casing where it serves to illuminate the lens 10 and brilliantly light the interior of the casing, the bulged or outwardly curved portion of the casing above the lamp acting as a reflector to cast the rays back upon the rear wall of the casing and more effectually illuminate the same, and the direction indicators 35. While I consider it no part of the invention, I may explain that the automobile number plate may be conveniently supported, by any suitable means, as by a bracket 56 connected to and depending from the casing, so that the light which passes through the opening 15 may illuminate the same.

As an extremely convenient means of operating the signaling device, I propose to mount upon an operating pedal of the automobile switch mechanism by which the circuits to the solenoids of the device may be opened and closed at the will of the operator.

The switch mechanism I have shown as comprising a plate 60, that may be attached to the brake pedal, for instance, by screws 61, and having apertures in its upper end through which push buttons 62 and 63 extend, the same being spaced a distance apart less than the width of the driver's shoe sole, so that he may depress both of them simultaneously with one foot, or, by shifting his foot in one direction or the other, avoid depressing one while depressing the other. An

element 65 of insulating material is secured to the underneath side of the upper end of the plate 60 by means of a bolt 66, and a contact spring 67 is clamped between the 5 respective bosses 65^a and 60^a of the element and plate. The contact spring (which is shown as laminated) extends out on each side of the bosses beneath the buttons 62 and 63 and are arranged to be forced, when said 10 buttons are depressed, against the heads of screws 68 and 69 which pass through lateral extension of the element 65 and have nuts 70 applied to their protruding ends whereby 15 electrical conductors may be conveniently attached to them.

In the diagram of Fig. 8, a branch conductor 71 is shown as leading from the solenoids 27 and 28 to one side of a battery B, the other side of the battery having connection, through the conductor 72, with the bolt 66, which it will be understood is in 20 electrical connection with the spring 67. An electrical conductor 73 connects the screw 68 with the winding of the solenoid 27, and 25 a conductor 74 connects the screw 79 with the winding of the solenoid 28. Consequently, when the button 62 is depressed a circuit is established from one side of the battery through the conductor 72, bolt 66, 30 spring 67, screw 68, conductor 73, the winding of the solenoid 27, and the conductor 71, to the opposite side of the battery, thus energizing the solenoid 27 and elevating the 35 right hand direction indicator (as viewed in Figs. 1, 3 and 4). It is clear that when the button 63 is depressed, a circuit will be established through the winding of the solenoid 28 and the other indicator will be elevated. Also, that when both buttons are 40 depressed at the same time, the direction indicators will be elevated simultaneously.

Having thus described my invention, what I claim is:—

1. A signaling device comprising an indication, a pair of indicators normally reposing in a position to conceal said indication and movable each independently of the other to a second position to indicate a direction, said indicators, when simultaneously occupying their respective second positions, allowing the display of the aforesaid indication.

2. A signaling device comprising a casing having a sight opening, an indication supported within the casing in a position to be observed through said opening, a pair of indicators supported within said casing in a position to normally conceal the aforesaid indication, means for moving each indicator independently of the other to a second position to indicate a direction, said indicators, when occupying their respective second positions, allowing the display of the aforesaid indication.

65 3. A signaling device comprising a casing

having a sight opening, means illuminating the interior of the casing, an indication supported within the casing in a position to be observed through the sight opening, a pair of indicators supported within the casing in 70 a position to normally conceal said indication, means for moving each indicator independently of the other to a second position to indicate a direction, said indicators, when occupying their respective second positions 75 at the same time, allowing the display of the aforesaid indication.

4. A signaling device comprising a casing having a sight opening, means illuminating the interior of the casing, an indication supported within the casing in a position to be observed through the sight opening, a pair of indicators pivotally supported upon substantially the same axis within the casing and normally reposing in a position 80 to conceal the aforesaid indication, and means for swinging each indicator from normal to a second position to indicate a direction, said indicators, when occupying their respective second positions at the same 85 time, allowing the display of the said indication, and the sight opening of the casing being of sufficient extent to reveal the indicators at all times.

5. A signaling device comprising a circular casing, a pair of indicators pivotally supported upon an axis substantially central of the casing and normally suspended one over and practically concealing the other, and means for swinging each indicator independently of the other to a second position to indicate a direction opposite to that indicated by the other, the casing having a segmental sight opening substantially concentric to the pivotal axis of the indicators and 100 coextensive with their movements.

6. A signaling device comprising a circular casing, a pair of indicators pivotally supported upon an axis substantially central of the casing and normally suspended one 110 over and practically concealing the other, means for swinging each indicator independently of the other to a second position to indicate a direction opposite to that indicated by the other, and an indication within 115 the casing located in a position to be concealed by the indicators when they are in normal position and revealed when both are simultaneously in their respective second positions, the casing having a segmental 120 sight opening substantially concentric to the pivotal axis of the indicators and coextensive with their movements.

7. A signaling device comprising a casing, an arbor supported within said casing, a 125 pair of indicators pivoted upon said arbor and normally depending side by side therefrom, a stop normally engaged on opposite sides by said indicators, and a pair of electromagnetic devices located within the cas- 130

ing and having connection one with each of said indicators whereby it may be moved from normal to a second position, said casing having an opening through which the 5 movements of the indicators are revealed.

8. A signaling device comprising a casing, an arbor supported within said casing, a pair of indicators pivoted upon said arbor and normally depending therefrom with one 10 of the indicators over and practically concealing the other, a pair of electromagnetic devices located within the casing and having connection one with each of said indicators whereby it may be moved from normal to a 15 second position, and an indication located within the casing in a position to be concealed by the indicators when in normal position but revealed when both simultaneously occupy their second positions, said casing having an opening through which the 20 movements of the indicators may be observed.

9. A signaling device comprising a casing, a tubular post within said casing, the casing 25 having an aperture in one of its walls through which the post extends, the post having an abutment bearing against the inner side of the casing wall, a supporting element applied to the protruding end of the 30 post and between which and the aforesaid abutment the adjacent portion of the casing wall is clamped, means remote from the post and extending through the supporting element and the casing wall, a member supported by said means within the casing, a 35 pair of electromagnetic devices supported by said member, a pair of indicators journaled upon the post and normally depending side by side therefrom, connections between each 40 of said indicators and one of the electromagnetic devices whereby said indicator may be swung from normal to a second position when the respective electromagnetic device is energized, and a lamp socket carried by 45 the inner end of the post, said socket being adapted to support a lamp for illuminating the interior of the casing, the electric conductors for the lamp and the electromag-

netic devices being adapted to enter the casing through said post.

50

10. A signaling device comprising a casing, a post within said casing, the casing having an aperture in one of its walls through which the post extends, the post having an abutment bearing against the 55 inner side of the casing wall, a supporting element applied to the protruding end of the post and between which and the aforesaid abutment the adjacent portion of the casing wall is clamped, means remote from 60 the post and extending through the supporting element and the casing wall, a member supported by said means within the casing, a pair of electromagnetic devices supported by said member, a pair of indicators 65 journaled upon the post and normally depending side by side therefrom, and connections between each of said indicators and one of the aforesaid electromagnetic devices whereby said indicator may be swung from 70 normal to a second position when the respective electromagnetic device is energized.

11. A signal device comprising a casing, an arbor supported within said casing, a pair of indicators pivoted upon said arbor, 75 a stop located below the arbor against the opposite sides of which the indicators are arranged to engage, and an electromagnetic means operatively connected to each indicator and acting, when energized, to move 80 the same away from the stop, while assisting, when deenergized, in holding the indicator against the stop.

12. In a signaling device, the combination of a pivotally supported indicator, a stop 85 for limiting the movement of the indicator in one direction, and an electromagnetic means operatively connected to the indicator and acting, when energized, to move the same away from the stop, while assisting 90 through its gravity, when deenergized, in holding the indicator against the stop.

In testimony whereof, I hereunto affix my signature.

BRENNAN B. WEST.
